CLAIM

The ornamental design for telephone set, substantially
as shown and described.

DESCRIPTION

FIG. 1 is an front, top and right side isometric view of
a telephone set showing my new design;

FIG. 2 is a rear elevational view thereof;

FIG. 3 is a left side elevational view thereof;

FIG. 4 is a top plan view thereof.

The broken line showing of a coiled cord in FIG. 4 is
for illustrative purposes only and forms no part of the
claimed design.
